US0D1088098S

(12) **United States Design Patent** (10) **Patent No.:** **US D1,088,098 S**
(45) **Date of Patent:** **** Aug. 12, 2025**

(54) **PROJECTOR**

(71) Applicant: **LG ELECTRONICS INC.**, Seoul

(KR)

(72) Inventors: **Eunbong Lee**, Seoul (KR); **Daihyung Ryu**, Seoul (KR); **Youngho Kim**, Seoul (KR)

(73) Assignee: **LG ELECTRONICS INC.**, Seoul (KR)

(**) Term: **15 Years**

(21) Appl. No.: **35/520,849**

(22) Filed: **Mar. 29, 2024**

(80) **Hague Agreement Data**

Int. Filing Date: **Mar. 29, 2024**

Int. Reg. No.: **DM/236793**

Int. Reg. Date: **Mar. 29, 2024**

Int. Reg. Pub. Date: **May 10, 2024**

(30) **Foreign Application Priority Data**

Nov. 7, 2023 (KR) 30-2023-0043850

(51) **LOC (15) Cl.** **16-02**

(52) **U.S. Cl.**

USPC **D16/230**

(57) **CLAIM**

The ornamental design for a projector as shown and described.

DESCRIPTION

1. Projector

1.1 : Front perspective view

1.2 : Back perspective view

1.3 : Front

1.4 : Back

1.5 : Left

1.6 : Top

1.7 : Bottom

1.8 : Reference view

1.9 : Reference view

The characteristic features of the design lie in the shape; the omitted right view is a mirror image of the left view; reproductions 1.8 and 1.9 show the states of use of the claimed design respectively; the broken lines shown in the reproductions depict portions of the projector and form no part of the claimed design; the shading lines are used to show the surface of the claimed design and do not represent

(Continued)

its surface ornamentation; the diagonal shading lines are used to show the transparent part and thin lines are drawn therethrough.

1 Claim, 9 Drawing Sheets
